CLAIM

The ornamental design for a flower pot cover, as shown and described.

DESCRIPTION

FIG. 1 is a perspective view of our new flower pot cover design;

FIG. 2 is a side elevational view thereof;

FIG. 3 is a top plan view thereof;

FIG. 4 is a bottom plan view thereof;

FIG. 5 is a side elevational view of the design of FIG. 1, the only difference being in the horizontal angle of the skirt;

FIG. 6 is a side elevational view of the design of FIG. 1, the only difference being in the near vertical angle of the skirt;

UNITED STATES PATENT AND TRADEMARK OFFICE
CERTIFICATE OF CORRECTION

Page 1 of 3

PATENT NO. : Des. 366,630

DATED : January 30, 1996

INVENTOR(S) : Donald E. Weder et al.

It is certified that error appears in the above-identified patent and that said Letters Patent is hereby corrected as shown below:

On the title page, please add page 2 to include the following:

--Figure 7 is a side elevational view of the design of Figure 1, the only difference being in the downward angle of the skirt;--

--Figure 8 is a perspective view of a second embodiment of our new flower pot cover design;--

--Figure 9 is a side elevational view thereof;--

--Figure 10 is a top plan view thereof;--

--Figure 11 is a bottom plan view thereof;--

--Figure 12 is a side elevational view of the design of Figure 8, the only difference being in the horizontal angle of the skirt;--

It is certified that error appears in the above-identified patent and that said Letters Patent is hereby corrected as shown below:

--Figure 13 is a side elevational view of the design of Figure 8, the only difference being in the near vertical angle of the skirt;--

--Figure 14 is a side elevational view of the design of Figure 8, the only difference being in the downward angle of the skirt;--

--Figure 15 is a perspective view of a third embodiment of our new flower pot cover design;--

--Figure 16 is a side elevational view thereof;--

--Figure 17 is a top plan view thereof;--

--Figure 18 is a bottom plan view thereof;--

--Figure 19 is a side elevational view of the design of Figure 15, the only difference being in the horizontal angle of the skirt;--
